(57) **CLAIM**

The ornamental design for an image processing machine for medical use, as shown and described.

DESCRIPTION

FIG. 1 is a front view of an image processing machine for medical use, showing the new design;

FIG. 2 is a rear view thereof;

FIG. 3 is a tight side view thereof;

FIG. 4 is a left side view thereof;

FIG. 5 is a top view thereof;

FIG. 6 is a bottom view thereof;

FIG. 7 is a cross sectional view thereof along line 7-7 omitting the internal configuration;

FIG. 8 is an end view thereof along line 8-8 omitting the internal configuration;

FIG. 9 is a partial enlarged end view thereof along line 9-9; and,

FIG. 10 is a perspective view thereof.
